UNITED STATES PATENT OFFICE.

GEORGE P. PALMER, OF BOSTON, MASSACHUSETTS.

DESIGN FOR A FLOWER-POT.

Specification forming part of Design No. 5,806, dated April 16, 1872.

To all whom it may concern:

Be it known that I, GEORGE P. PALMER, of Boston, of the county of Suffolk and State of Massachusetts, have invented or produced a new Ornamental Design for a Double-Vase Flower-Pot; and do hereby declare the same to be described as follows, and to be represented in the accompanying drawing, of which—

Figure 1 is a top view, Fig. 2 a side elevation, and Fig. 3 a vertical and transverse section, of such flower-pot.

The flower-pot has two conical vases, A B, with a bottom, *a*, common to both. The inner vase rises above the outer, the two being concentric with a water-space between them

and encompassing the inner one. The upper part of each vase is flared outward in the curved form, and is corrugated, all being as shown, the corrugations forming a series of spouts and giving to the two vases a very pleasing ornamental appearance. A hole, *c*, is arranged through the side of the inner vase, near the bottom thereof.

I claim as my invention—

The design, as shown and described, for the double-vase flower-pot.

GEO. P. PALMER.
